UNITED STATES PATENT OFFICE.

LINFORD S. STILES AND FREDERICK S. BENSON, JR., OF BROOKLYN, NEW YORK.

KNOCKDOWN SHIPPING-CASE.

No. 888,548.

Specification of Letters Patent.

Patented May 26, 1908.

Application filed April 16, 1907. Serial No. 368,546.

To all whom it may concern:

Be it known that we, LINFORD S. STILES and FREDERICK S. BENSON, Jr., of Brooklyn, county of Kings, and State of New York, have invented an Improvement in Knockdown Shipping-Cases, of which the following is a specification.

Our invention has reference to knock down crates and consists of certain improvements which are fully set forth in the following specification and shown in the accompanying drawings which form a part thereof.

The object of our invention is to provide a construction of case or crate which may be collapsed and thereby condensed as to shipping space occupied in return transportation to the shipper, the construction being such that it shall be simple and cheap to construct, strong and durable when packed and subjected to transportation handling, and compact when collapsed or condensed so as to occupy a minimum space during return shipment.

In carrying out our construction in practical form, we employ a bottom and shallow sides in rigid form, and combine therewith two pivoted ends, hinged upper sides and locking devices for locking the sides to the ends so as to form a rigid box-like case or

crate.

Our invention also comprises in the above structure locking devices for locking the parts in collapsed form.

Our invention further embodies details of construction which, together with the above features, will be better understood by reference to the drawings, in which:

Figure 1 is a plan view of our improved shipping case or crate in open condition; Fig. 2 is a vertical sectional elevation of the same on line 2—2; Fig. 3 is a plan view of the same in collapsed condition; Fig. 4 is a longitudinal section of Fig. 3 on line 4—4; Fig. 5 is a cross section of Fig. 4 on line 5—5; Fig. 6 is a cross section of Fig. 2 on line 6—6; Fig. 7 is a cross section corresponding to Fig. 5 with the lid folded in a modified form; Fig. 8 is a plan view of one end of the case in the form shown in Fig. 7; Fig. 9 is a perspective view of a reinforcing plate for the hinges; and Fig. 10 is a view showing a modified form of retaining catch.

A is the bottom and may be made in any manner desired, but preferably of cross bars and longitudinal boards and reinforced by two longitudinal base strips A' upon which

the crate may rest and by which the bottom proper is supported slightly above the ground. This bottom is provided with side boards D' rigidly secured in place by screws or otherwise. These fixed sides have hinged to them the upper adjustable side sections D² which, together with the parts D', constitute the full sides D of the case or crate.

B B are the two ends and these are preferably made solid. They are hinged to the bottom portion of the case in any suitable manner so as to be adapted to be folded inward upon the bottom A. In the particular form shown these end frames B are pivoted at b to inwardly bent ends of wire spring arms B' secured to the bottom A at d. In this manner the end frames rest solidly on the bottom and normally hold their position when raised. The same is true when they are folded down as the springs act to retain them in such adjustments just as a knife blade will maintain its position open or shut. While this type of spring hinge is cheap and effective we do not restrict ourselves to it as various forms of hinge joints may be employed, as will occur to those skilled in the art. The hinged sides D² are preferably formed of slats and provided with upright bars R which obstruct the ends D from being forced inward when the sides are in position shown in Figs. 1, 2 and 6. These sides D² are hinged to the rigid sides D' by links d' of looped wire. Such hinges are very cheap, but other types of hinges may be used if so desired.

E are two top boards and are hinged to the sides D² by looped hinges e of wire but preferably triangular in outline as shown in Fig. 6 to fit to the parts D' and E in their angular position to each other when the crate is open. The ends of these boards E are provided with transverse bars i, which fit down into recessed portions I on the top of the end frames and thereby prevent the said frames from being forced outward. It will thus be seen that the end frames are held in one direction by the bars i and in the other direction by the bars R thereby making a strong and rigid case.

To lock the sides D² and top boards E to the end frames B, we provide looped wire frames F which are hinged to the bottom at f, the hinge being formed by inwardly turned portions extending through the base timbers A' and turned over as at F' to prevent said hinge portions from becoming disengaged. These

looped frames F extend upward upon the outside of the side frames, thence across the top over the end frames B and are snapped under locking studs C of metal secured to the 5 top and middle of the end frames. These studs have under cut portions formed by upwardly directed oblique slots c and when the transverse portions of the frames F are snapped into said slots no upward pressure 10 of the top of the case can disengage said frames F from their locking position. It will also be impossible for said frames F to move outward and they will have no tendency to move inward from disengagement 15 with the locking studs except under specific hand manipulation.

Ordinarily, the cases may be left open between the two top boards E E', but in some cases it is desirable to provide a cover or lid 20 and in such cases we may employ a central lid H resting at each end on the top middle portions of the end frames and hinged to one of the top boards by links h and adapted to be locked to the other top board by any ordinary fastening such as would employ a staple or pad-lock. In our illustrations we have provided such a cover or lid but it may be omitted if so desired. When employed, this lid is provided with notches H' at each end to 30 fit over the studs C. It will be evident that while we have shown the sides, top and bottom as formed of slats forming an open or ventilating structure of shipping case or crate that said parts may be made solid or in 35 any other way to adapt them to the particular use to which they are to be put. Such details are not germane to the spirit of our invention.

To collapse our improved crate, it is first 40 necessary to spring by hand the looped frames F out of engagement with the studs C and move them outward; then disengage the top boards E and sides D²; then fold inward the end frames B; then fold upon the 45 said end frames the sides D² and top boards E and also the lid H if employed; and then fold inward the two looped locking frames F to the positions shown in Figs. 3, 4 and 5 and lock them under the catch G having the 50 hooked portions G' under which the said frames snap. In this condition the case is not only in collapsed and condensed form but is also in a locked form in which it may be shipped without disengagement of the 55 parts. The several parts rest directly one upon the other and hence great solidity to the condensed structure is secured. In place of the catches G', we may employ hinged hooks G² looped on the side wires of 60 the looped frames F and adapted to engage holes G³ as shown in Fig. 10, or any other suitable form of retaining catch may be employed.

In some cases the strain upon the wood of 65 the crate is severe and more especially is this

true when the crate is made of soft wood, and to increase the strength of the hinged connections between the several parts where the links d' e and h, or either of them occur, the wood may be reinforced by metal clips such as shown at J in Fig. 9 having holes for the links and prongs J' for engaging the wood. 70

The manner of folding the movable parts of the case or crate shown in Figs. 3, 4 and 5 is most preferred, but if desired said parts 75 may be folded as shown in Figs. 7 and 8.

Our improved knock down or collapsible case or crate is not only cheap to construct and strong and durable in use, but is easily manipulated so that very little time is consumed in adjusting its parts either for outgoing shipment or return shipment. 80

We have shown what we believe to be the most preferred form of embodiment of our invention for commercial use but we do not 85 restrict ourselves to the details thereof as they may be modified without departing from the invention.

Having now described our invention, what we claim as new and desire to secure by Letters Patent, is:—

1. In a knock down shipping case, the combination of a bottom, end frames hinged close to the bottom and adapted to fold upon the bottom, sides hinged at a distance above 95 the bottom and adapted to fold inward over the ends when folded down upon the bottom and against the ends when raised and lock them in upright position, and two hinged looped locking frames hinged to the bottom 100 at the base of the end frames and constructed to fit against the side frames and over the end frames.

2. In a knock down shipping case, the combination of a bottom, end frames hinged to the bottom, sides hinged to the bottom at a higher elevation than the end frames and adapted to fold inward against the ends and lock them in upright position, two hinged looped locking frames hinged to the bottom 105 at the base of the end frames and constructed to fit against the side frames and over the end frames, and locking devices on the end frames 110 for engaging the looped locking frames and holding them in locking position.

3. In a knock down shipping case, the combination of a bottom, end frames hinged to the bottom, hinged sides adapted to fold inward against the ends and lock them, two hinged looped locking frames hinged to the 115 bottom at the base of the end frames and constructed to fit against the side frames and over the end frames, and locking devices on the end frames consisting of studs having under-cut portions for engaging the looped locking frames and holding them in locking position.

4. In a knock down shipping case, the combination of a bottom, end frames hinged to the bottom, hinged sides adapted to fold 120 inward against the ends and lock them against 125

- inward movement, two top boards hinged to the hinged sides having locking engagement with the end frames to hold them against outward movement, and two hinged looped locking frames hinged to the bottom at the base of the end frames and constructed to fit against the side frames and over the top boards and end frames.
5. In a knock down shipping case, the combination of a bottom, end frames hinged to the bottom, spring hinges for the end frames to normally hold them in open position, hinged sides adapted to fold inward against the ends and lock them, and two hinged looped locking frames hinged to the bottom at the base of the end frames and constructed to fit against the side frames and over the end frames.
6. In a knock down shipping case, the combination of a bottom, end frames hinged to the bottom, hinged sides adapted to fold inward against the ends and lock them, two hinged looped locking frames hinged to the bottom at the base of the end frames and constructed to fit against the side frames and over the end frames, and means for locking the looped locking frames to the bottom portion of the case at a distance from their hinged points when the case is collapsed.
- 30 7. In a knock down shipping case, the combination of a bottom having sides D' rigidly secured to it, end frames hinged to the bottom at a lower level than the top of the sides D', hinged sides hinged to the sides D' adapted to fold inward against the ends and lock them in open position, two hinged looped locking frames hinged to the bottom at the base of the end frames and constructed to fit against the side frames and over the end frames, and means on the sides D' for locking the looped locking frames to the bottom when the case is in collapsed form.
8. In a knock down shipping case, the combination of a bottom, end frames hinged to the bottom, hinged sides adapted to fold inward against the ends and lock them respectively against movement in one direction, two top boards hinged to the hinged sides having locking engagement with the end frames to lock them respectively against movement in the other direction, two hinged looped locking frames hinged to the bottom at the base of the end frames and constructed to fit against the side frames and over the end frames, and a lid portion hinged to one of the top boards and extending toward the other top board.
- 50 9. In a knock down shipping case, the combination of a bottom, two end frames hinged to the bottom so as to fold inward upon it and having locking recesses in their edges, longitudinal parts extending from end frame to end frame and provided with bars engaging the recesses, and adjustable means for holding the longitudinal parts in contact with the end frames.
5. In a knock down shipping case, the combination of a bottom having fixed sides D' secured to it, hinged side frames D² hinged to the sides D' and provided with means for preventing the end frames being turned inward, top boards E hinged to the hinged sides frames and having means engaging the end frames for preventing them being turned outward, and looped wire frames F hinged to the bottom and extending over the end frames for holding the hinged sides D² and top boards E in contact with them.
10. In a knock down shipping case, the combination of a bottom having fixed sides D' secured to it, hinged side frames D² hinged to the sides D' and provided with means for preventing the end frames being turned inward, top boards E hinged to the hinged sides frames and having means engaging the end frames for preventing them being turned outward, and looped wire frames F hinged to the bottom and extending over the end frames for holding the hinged sides D² and top boards E in contact with them.
11. In a knock down shipping case, the combination of a bottom having fixed sides D' secured to it, hinged side frames D² hinged to the sides D' and provided with means for preventing the end frames being turned inward, top boards E hinged to the hinged sides frames and having means engaging the end frames for preventing them being turned outward, looped wire frames F hinged to the bottom and extending over the end frames for holding the hinged sides D² and top boards E in contact with them, and means on the end frames for locking the looped wire frame in position.
12. In a knock down shipping case, a bottom in combination with end frames hinged close to and at the ends of the bottom so as to fold down toward each other directly upon the bottom, two series of longitudinal parts extending from end frame to end frame and hinged together and each series hinged to the sides of the bottom at an elevation considerably above the hinge points of the ends and adapted to be folded against the sides and top of the end frames when raised and over them when they are folded down, and means for locking the end frames and longitudinal parts together in their open or shipping position.
13. In a knock down shipping case, a bottom in combination with end frames hinged at the ends of the bottom so as to fold down toward each other, two series of longitudinal parts extending from end frame to end frame and hinged together and adapted to be folded against the sides and top of the end frames, and means for locking the end frames and longitudinal parts together in their open or shipping position.
- In testimony of which invention, we have hereunto set our hands.
